UNITED STATES PATENT OFFICE.

JAMES W. STEELE, OF CHICAGO, ILLINOIS.

SEMAPHORE OR GATE.

SPECIFICATION forming part of Letters Patent No. 443,732, dated December 30, 1890.

Application filed September 6, 1890, Serial No. 364,188. (No model.)

To all whom it may concern:

Be it known that I, JAMES W. STEELE, of Chicago, in the county of Cook and State of Illinois, have invented certain new and useful

5 Improvements in Semaphores or Gates, of which the following is a full, clear, and exact description, reference being had to the accompanying drawings, forming a part of this specification, in which—

10 Figure 1 is a side view showing the frame of a railway-gate, the casing being removed to show the operating mechanism. Fig. 2 is a view of the same, taken in a plane at right angles thereto. Fig. 3 is a like view to that 15 shown in Fig. 1, representing the parts in reverse positions, respectively. Fig. 4 is a detail view of a portion of the operating mechanism shown in a reverse position from that illustrated in Fig. 3. Fig. 5 is a horizontal 20 sectional view taken upon the line xx , Fig. 3. Fig. 6 is a side view of a modification of said invention, the same being applied to a semaphore, in which the case is shown in section to display the working parts. Fig. 7 is a detail 25 view showing the semaphore and its support, taken in a plane at right angles to that indicated in Fig. 6; and Fig. 8 is a detail view representing a modified form of electrical releasing device.

30 Corresponding letters of reference in the different figures designate like parts.

The primary object of my invention is to operate a semaphore or gate by means of a single impulse and to lock the same automatically in one or another position whenever the same is reached by said gate or semaphore.

40 A further object is to provide means for actuating said gate or semaphore in a given direction, by hand or otherwise, and automatically to reverse its position by means of an electric releasing-trigger, the electric circuit with which may be closed by means of a passing train. Moreover, I desire to provide 45 novel means for cushioning the moving arm of the semaphore or gate upon reaching its limit of movement and when acted upon by the locking device, all of which is hereinafter more specifically set forth and definitely 50 claimed.

Referring to the drawings, a represents a

hollow standard or case, preferably made of cast metal, near the top of which, mounted in suitable bearings, is a shaft b , to which is rigidly attached a counterpoise-arm c , adapted 55 to move in the manner clearly indicated in Fig. 3, and which may be employed as a gate; or by elevating it, as shown in Fig. 6, and connecting it, as hereinafter stated, it may be used as a semaphore.

60 Loosely pivoted to the support a , preferably at a' , is a bar d , the lower end of which is adapted to swing back and forth. Loosely pivoted to the bar d at d' are two bars or links $e e'$, the lower ends of which are attached to 65 lever-arms $f f'$, whose outer ends are pivoted to the frame at $f^2 f^2$, while to the inner or movable ends are attached spiral springs $g g'$, which are in turn connected by means of rods $g^2 g^2$ to a cross-bar g^3 , pivotally attached to 70 the bar d near its upper end. The ends of said cross-bar are in turn connected by means of links $h h$ to a like cross-bar h' , rigidly attached to the shaft b . A crank-arm j is also attached to the shaft b , and is loosely connected at its end with a toggle brace or stop 75 consisting of the members $k k'$, loosely jointed to an intermediate member k^2 , which is extended at right angles therefrom for the purpose of receiving a pin k^3 , around which is 80 bent a spring k^4 , for the purpose of straightening said joint. The member k' is pivoted at l' to an arm l , and is provided with a lateral arm m , having a pin m' upon the end, adapted to engage with flanges $n' n^2$ upon an 85 arm n , attached to the bar e' and projecting obliquely therefrom. The bar l is pivoted at l^2 to the frame, and upon the opposite end is preferably formed a lug l^3 , through which is 90 loosely passed a curved rod o , Figs. 1 and 3, the ends of which are loosely secured to lugs $o' o'$, attached to the frame. Interposed between the lug l^3 and the lugs $o' o'$ are spiral springs $o^2 o^2$, which serve to hold the bar l in a normally horizontal position, but to permit 95 a slight movement of its end.

The bar d is normally held in the position shown in Fig. 1, preferably by means of a spring p , which is attached by a link or otherwise to the lower end of said bar, as shown.

100 The bar d may be moved in an opposite direction by means of a rod p' and lever p^2 , as

shown in Fig. 3, or otherwise. A bar q , pivoted to the frame at q' , is pressed against a friction-roller d^2 , loosely mounted upon the bar d near its lower end by means of a spring 5 q' . A depression q^2 in the bar q serves to engage said roller and hold bar d in an abnormal position, as shown in Fig. 3, so long as the bar q is pressed against it with sufficient force, which may be accomplished by means 10 of a latch r , loosely pivoted to the frame and provided with a notch therein for the reception of the end of said bar. An electro-magnet s , Figs. 3 and 6, is placed in operative proximity to said latch, which forms an armature therefor, and one of the terminals of said magnet is connected by means of a wire s' with a contact-point s^2 , secured to but insulated from a railway-rail t . The other terminal is connected by means of a wire s^3 , in 15 which a battery s^4 is interposed, with a tripping device u , pivoted to said rail and provided with a contact-point s^5 in operative proximity to point s^2 , but normally separated from it by means of a rubber or other spring 20 v . Upon the passage of a train the tripper u is depressed by the car-wheel, thereby closing the circuit and moving the armature r , thus releasing the bar q , which permits the bar d to assume its normal position.

25 30 A form of electrical releasing device which is preferred to that last described is shown in Figs. 1 and 8. A rod q^3 is extended upwardly from the end of the bar q , and is passed loosely through a flat plate w , which is pivoted at w' , and the oscillation of which is limited by means of stops w^2 , the lower one of which is so placed as to permit the plate to fall to an oblique position with reference to the rod, thereby clamping the latter and preventing its descent, while the rod may be pushed upwardly therein with the utmost freedom. The plate w is either made of soft iron, or an armature w^3 is attached thereto, in proximity to which is placed an electro-35 magnet y , connected with the tripper u in the manner described. Upon the depression of the tripper the magnet draws the plate to a horizontal position, as shown in dotted lines, thereby releasing the rod q^3 and permitting 40 the bar d to assume its normal position.

45 50 In Figs. 6 and 7 I have shown a modification of said invention as applied to a semaphore, which, being the equivalent of the gate c , I have designated by the same letter. As it is desirable to construct a semaphore much lighter than a gate, I have pivoted the same upon the top of a post a' , attached sprocket-wheels $c' c'$ to the axis of the semaphore and to the shaft b , respectively, and have connected said wheels by means of a chain c^2 . Thus the rotation of the shaft c serves to move the semaphore-arm in the same way as if it were attached to said shaft.

Having thus described the mechanism involved in my invention, I will describe its operation.

When the bar d is in its normal position, (see Fig. 1,) the springs $g g'$ are under substantially equal tension and the gate c stands vertically. It should be borne in mind that 70 the power required to move the bar d back and forth, however rapidly, is but nominal, while that required to move the gate with equal rapidity would be considerable. Hence I have interposed the springs $g g'$ to overcome the inertia of the gate and move it with comparative slowness, while the bar d is vibrated suddenly. The two do not move synchronously, and, owing to the inertia of the gate, it is possible in practice to move the 75 bar d back and forth to the full extent of its movement, if done with sufficient speed, without actuating the gate at all; but if a stop is made long enough to overcome the inertia of the gate it is then moved with 80 certainty. When said bar is moved to the extreme left, the spring g is suddenly expanded, as shown in Fig. 3, and tends to actuate the semaphore, as indicated by the arrow shown in said figure, the movement continuing until it assumes the position indicated in dotted lines. This much of my invention is shown in my application, filed April 29, 1890, Serial No. 349,928; but it is important automatically to lock said gate or semaphore 85 either in a vertical or horizontal position 90 when one or the other is reached and to so retain it until the bar d is again moved. To accomplish this result I have pivoted the lower end of the knee-joint mechanism at a 95 point equally distant from the respective positions of the crank-pin of the arm j when the gate is raised and lowered. In swinging the bar d from left to right the pin m' is 100 brought into contact with the flange n' , (see Fig. 1,) which is being moved laterally, pushes the arm m down, and bends the knee-joint, as in Fig. 3, which shows the pin in the act of leaving the flange n . Upon the completion 105 of the gate movement, which enables the 110 crank j to assume the position shown in dotted lines, the knee-joint becomes straightened when the pin m' is in operative proximity to the flange n^2 . Upon a reverse movement of the bar d the action of the flange n^2 serves to 115 bend the joint and permit the gate or 120 semaphore, as the case may be, to be reversed, the straightening of the knee-joint in each case serving to limit its movement. In order to cushion said gate in its movement, I provide 125 the springs o^2 . This is especially desirable in gates; but for light semaphores the construction shown in Fig. 6 may be employed. Upon the approach of a train the bar d may be moved by means of a lever p^2 , thus closing the 130 gate. The train having passed to a sufficient distance the wheels are brought into engagement with the tripper u , which serves to withdraw the armature r and release the bar d , which is drawn to its normal position by 135 means of the spring p , thus opening the gate. By placing the tripper farther away and em-

ploying it in connection with a semaphore it may be utilized as a distance-signal for the operation of railway-trains.

Having thus described my invention, I 5 claim—

1. In a semaphore or gate, the combination of the bar *d* and its intermediate connections in operative connection with said semaphore or gate, a knee-joint brace having one end attached to a crank-arm of the gate and the other pivoted centrally between the two extreme points of movement of said crank, and means for temporarily bending said knee-joint with each vibration of the bar *d*, substantially as shown and described. 15

2. In a semaphore or gate, the combination of the bar *d* and the intermediate double toggle-joint mechanism, as specified, in operative connection with said semaphore or gate, a knee-joint brace having one end attached to a crank-arm of the gate and the other pivoted to a cross-bar at a central point between the two extreme points of movement of said crank, said cross-bar being pivoted to the frame at one end and attached to springs at the other, for holding it normally in a given position, and means for bending said knee-joint with each vibration of the bar *d*, whereby said gate or semaphore may be automatically unlocked and locked in position with each vibration of the bar *d* and the movement of the gate or semaphore cushioned at its extremity, substantially as shown and described. 25

3. The combination of the bar *d*, a spring for normally holding the same in a given position, pivoted and spring-actuated bar *q* in operative connection with said bar *d*, means for temporarily locking said bar *q* when the bar *d* is in an abnormal position, and an electric releasing device in communication with a tripper connected with the railway-track, substantially as shown and described. 35

4. The combination, with a semaphore or gate, of a knee-joint-locking device held nor-

mally straight by means of a spring, a laterally-extended arm rigidly connected with one member of said knee-joint, and means for automatically tilting said arm in one or another direction preliminary to the shifting of the semaphore or gate, substantially as shown 45 and described. 50

5. The combination, with the swinging bar *d* and its intermediate mechanism, as described, in operative connection with a crank-arm for operating a semaphore or gate, of a knee-joint-locking device held normally straight by a spring, one member of said device consisting of a bent arm, the free end of which is in operative proximity to a movable arm provided with obliquely-placed flanges thereon, one or the other of which is adjusted to engage said bent arm alternately, and means, as described, for moving said flanged arm with each movement of the bar *d*, whereby said knee-joint may be automatically bent and the semaphore 65 or gate unlocked simultaneously with the movement by which it is actuated, substantially as shown and described. 60

6. The combination, with a semaphore or gate pivotally mounted upon a shaft, of the crank-arm *j*, a double-acting knee-joint-locking device for automatically locking the same in its extreme positions, a horizontal bar pivoted at one end to the frame, to which bar said knee-joint is in turn pivoted, and 70 spring-buffers attached to the free end of said horizontal bar, whereby said semaphore or gate may be cushioned upon reaching the opposite limits of its movement, substantially 75 as shown and described. 80

In testimony whereof I have signed this specification, in the presence of two subscribing witnesses, this 29th day of August, 1890.

JAMES W. STEELE.
